KEY ASSEMBLY FOR MUSICAL INSTRUMENTS

Emil J. Ens, Newark, N. J., assignor to Magnus Harmonica Corporation, Newark, N. J., a corporation of New Jersey

Application July 5, 1951, Serial No. 235,288

10 Claims. (Cl. 84—376)

1

The present invention relates to a key assembly for musical instruments.

An object of the invention is to provide a key assembly and key-operating mechanism for musical instruments, particularly of the type employing a number of keys, that is inexpensive to manufacture and that makes the assembly operation simpler and less expensive. Another object of the invention is to provide a key assembly which provides a uniform action for the operation of each of the keys. Other objects and advantages of the invention will be apparent and best understood from the following description and the accompanying drawings in which:

Fig. 1 is a plan view of a key assembly for a musical instrument embodying the present invention;

Fig. 2 is a front elevational view of the key assembly illustrated in Fig. 1;

Fig. 3 is a section view taken along the line 3—3 of Fig. 1;

Fig. 4 is a plan view of certain parts of the key assembly illustrated in Figs. 1 to 3;

Fig. 5 is an elevational view of the portions of the key assembly illustrated in Fig. 4; and

Fig. 6 is a perspective view of a key-actuating member for the key assembly illustrated in Figs. 4 and 5.

In the accompanying drawings a key assembly for an accordion has been illustrated and will be described hereinafter. However, it will be understood that a key assembly embodying my invention may be employed in other types of key-operated musical instruments by suitable changes.

Referring now to the drawings in detail and particularly to Figs. 1 and 3, there is an end plate 10 of an accordion which has a series of spaced openings 11 therein. Each of the openings 11 in the end plate 10 communicates with a reed or other sound-producing instrumentality (not shown) so that by opening and closing the openings 11 in an appropriate manner, the desired sound or melody may be produced in the usual manner.

Secured to the face of the end plate 10 there is a base 12 which supports a cover 13 thereon. The base and cover support a key assembly, indicated generally at 14, in operating position with respect to the openings 11 in the end plate 10. The key assembly 14 includes a series of independently movable keys 15, which are mounted side by side and each of which has an arm 16 that extends over one of the apertures 11 in the end plate 10. Each of the keys 15 also has a forwardly extending arm 17 that carries a button

2

18 thereon that extends through an opening 19 in the cover 13. Each of the keys 15 is pivoted, intermediate its ends, as will be described hereinafter, and is manually movable by pressing on the buttons 18 in a direction to open the air passageways or openings 11 in the instrument as desired in the playing of the instrument.

The rear faces of the arms 16 are flat and these faces are resiliently held in engagement with the end plate 10 so as to close the openings 11 therein by a key-actuating member 20. The key-actuating member 20 is preferably made from one piece of a resilient plastic material and consists of a body portion 21 that engages with and bears against the inside of the cover 13 so as to anchor or hold the body in fixed position. Extending along one edge of the body 21 and formed integrally therewith, there is a series of spaced spring fingers 22 which in this case extend at an angle to the body 21. Each of the spring fingers 22 extends through an opening 23 in one of the keys 15 of the series of keys and engages with the bottom of the forwardly extending arm 17 thereof. The spring fingers 22 urge the forwardly extending arms 17 upward and resiliently hold the rear faces of arms 16 against the end plate 10. The keys may be moved to open the passageways by depressing the buttons 18 on and the forwardly extending arms against the resiliency of the spring fingers and when the buttons 18 are released, the spring fingers will automatically return the keys to closed position.

The edge of the body 21 of the resilient key-actuating member 20 extending between the spaced spring fingers 22 forms shoulders 24 that are seated in slots 25 cut in the top of forwardly extending arms 17 of the keys on each side of the openings 23 through which the spring fingers pass and the keys 15 pivot about the shoulders 25 in their movement from open to closed position as described above.

For ease of assembly and to obtain uniform action of the keys, the resilient key-actuating member 20 is preferably made from one piece of a resilient plastic material. Suitable plastics from which the key-operating member or spring 20 may be made are polystyrene, synthetic linear super polymers such as nylon, vinyl chloride polymers, water insoluble cellulose ether, plasticized cellulose esters, vinyl ester polymers or acrylic polymers. Such materials have been found to be extremely durable and to maintain uniform resiliency during their life. The key-actuating member may be molded or extruded and machined from such materials in the usual

manner. However, if desired, the key-actuating member may be made of a suitable metal.

As indicated in Fig. 4, the keys 15 may be assembled in proper relation to each other on the resilient key-actuating member 20 to form the key assembly 14 and this assembly can then be inserted as a unit in the cover 13. This arrangement greatly simplifies the assembly operations over constructions where individual springs are used for each key and it also reduces the cost of the key assembly.

It will be understood that various changes and modifications may be made in the embodiment of the invention illustrated and described herein without departing from the scope of the invention as defined by the following claims.

I claim:

1. A key assembly for a musical instrument comprising a series of independently movable keys and a key-actuating member of resilient plastic material having a series of spaced fingers thereon, each of said spaced fingers engaging with one key of the series of keys and resiliently urging said key in one direction, said key being depressable manually in an opposite direction.

2. A key assembly for a musical instrument comprising a series of independently movable keys, said keys being pivoted at points intermediate their ends and being movable about said pivot points in the opening and closing of air passageways in a musical instrument, and a key-actuating member of resilient plastic material, said key-actuating member having a series of spaced fingers formed integrally therewith, each of said fingers engaging with one of the keys of said series of keys and resiliently urging said key in one direction about its pivot point.

3. A key assembly for a musical instrument comprising a series of independently movable keys, each of said keys having an opening therein at a point intermediate its ends and a key-actuating member of resilient plastic material on which said keys are pivotally supported, said member having a series of spaced spring fingers formed integrally therewith, each of said fingers extending through the opening in one of the keys of said series of keys and engaging with and resiliently urging said key in one direction.

4. A key assembly for a musical instrument comprising a series of independently movable keys, each of said keys having an opening therein intermediate its ends and slots in one surface thereof adjacent said opening, and a key-actuating member of resilient plastic material, said key-actuating member consisting of a body having a series of spaced spring fingers extending along one edge thereof and shoulders extending between the spaced spring fingers, said shoulders engaging with the slots in the keys and pivotally supporting the keys on said member for movement in opening and closing air passageways in the instrument, each of said spring fingers extending through the opening in one of the keys of said series of keys and engaging with and resiliently urging said key in one direction about said member.

5. A key assembly for a musical instrument comprising a series of independently movable keys, each of said keys having an opening therein intermediate its ends and slots in one surface thereof adjacent said opening, a key-actuating member of resilient plastic material, said key-actuating member consisting of a body having a

series of spaced spring fingers extending along one edge thereof and shoulders extending between the spaced spring fingers, said shoulders engaging with the slots in the keys and pivotally supporting the keys on said member for movement in opening and closing air passageways in the instrument, each of said spring fingers extending through the opening in one of the keys of said series of keys and engaging with and resiliently urging said key in one direction about said member and means for anchoring the body of said key-actuating member in a fixed position.

6. A key assembly for a musical instrument comprising a series of independently movable keys, each of said keys having an opening therein intermediate its ends and slots in one surface thereof adjacent said opening, a key-actuating member consisting of a body having a series of spaced spring fingers extending along one edge thereof and shoulders extending between the spaced spring fingers, said shoulders engaging with the slots in the keys and pivotally supporting the keys on said member for movement in opening and closing air passageways in the instrument, each of said spring fingers extending through the opening in one of the keys of said series of keys and engaging with and resiliently urging said key in one direction about said member and a cover extending over said keys, said cover engaging with and holding the body of the key-actuating member in a fixed position.

7. A key assembly for a musical instrument comprising a series of independently movable keys having arms extending over and closing air passageways in a musical instrument and arms accessible for manual operation thereof, each of said keys having an opening therein intermediate its ends and a key-actuating member of resilient plastic material on which said keys are pivotally supported, a series of spaced spring fingers carried by said key-actuating member, each of said spring fingers extending through the opening in one of the keys of said series of keys, said spring finger engaging with the respective keys of the series of keys and resiliently urging the keys in a direction to close the air passageways in the instrument.

8. A key-actuating member for resiliently maintaining a series of keys of a musical instrument in closed position which comprises a body of resilient plastic material, a series of spaced spring fingers formed integrally with said body and extending from said body along one side thereof, and shoulders extending between adjacent fingers of said series of fingers.

9. A key-actuating member for resiliently maintaining a series of keys of a musical instrument in closed position as described in claim 8 wherein said body and spring fingers are formed from polystyrene.

10. A key-actuating member for resiliently maintaining a series of keys of a musical instrument in closed position which comprises a body of resilient plastic material, a series of spaced spring fingers formed integrally with said body and extending at an angle from said body along one side thereof, and shoulders extending between adjacent fingers of said series of fingers.
